FORM FOR TEXTILE MATERIAL
OR THE LIKE

Jacob M. Field, Brooklyn, N. Y.

Application September 3, 1947, Serial No. 771,877

6 Claims. (Cl. 206—50)

1

The present invention comprises a new article of manufacture particularly adapted for use in the display or packaging of sheet material such as textile material that is sold or delivered in relatively long lengths of constant width. The new article comprises a structure that may be readily assembled into a sturdy framework or form about which sheet material may be wrapped as on a board.

As compared to articles heretofore in use in the textile industry for the same or similar purpose, the article of the present invention may be produced at substantially less cost and is lighter in weight.

The new article is entirely composed of foldable material, such as cardboard, and is readily assembled by folding blanks of the material along scored lines thereon. Thus, a plurality of the articles before assembly can be conveniently stored or shipped as blanks thus saving shipping space.

As forms or "boards" upon which textile or other material is wound are ordinarily used but once and then discarded, it is important that the cost thereof be low. It is also important that their construction be such that they do not collapse or become distorted under the weight of the material wrapped about them.

The article of the present invention is so constructed as to meet both these requirements. Also storage and shipping space is conserved when the articles are stacked before assembly.

For a better understanding of the invention, reference may be had to the accompanying drawing of which:

Fig. 1 is a perspective view of a form embodying the invention and comprising an outer cover member and an inner brace member;

Fig. 2 is a plan view, on a reduced scale, of a scored blank from which the brace member of Fig. 1 may be assembled by folding;

Fig. 3 is an enlarged perspective view of the brace member of Fig. 1;

Fig. 4 is a perspective view illustrating an alternative construction of brace member for use with the outer cover member of Fig. 1; and

Fig. 5 is a plan view of a scored blank foldable into the brace member of Fig. 4.

In the embodiment of the invention illustrated in Fig. 1, the outer cover member is indicated at 2 and inner brace member at 4. Member 2 may be of conventional box type construction. The dimensions of member 2 will depend upon the particular material with which the article is to be used, but the depth thereof will be relatively shallow and the width substantially less than the length; the shape of the member generally approximating that of a board. Member 2, in the particular embodiment of the invention illustrated in Fig. 1 has a bottom wall 6, side walls 80

2

8, a top wall formed of sections 10 and 10a adhesively secured together at their overlapping edges and end walls 12 each provided with a flap 12a underlying the top wall. A tab or tongue 14 on each end of the top wall section 10 extends over the adjacent end wall 12 and into a slot 16 in the fold between the bottom and end walls and serves to keep the end wall in position while permitting retraction thereof for access to the interior of the member 2. Member 2 may be readily assembled from a single scored blank as will be apparent to those skilled in the art. Any other conventional construction which permits access through either or both ends of the member 2 could be used in the article of Fig. 1.

The inner or brace member 4 comprises a base portion 18 having integrally joined thereto a four walled structure comprising interlocked strips 20 and 22, each of a height substantially equal to the depth of member 2, and side walls 24 which are integral with the base portion 18 and which terminate in strips 26 underlying the top wall 10—10a of the outer member. With the above described construction of the brace member 4, the structure formed by the strips 20 and 22 provides reinforcement for the central portion of member 2 and prevents collapse or distortion thereof. The base portion 18 provides additional rigidity crosswise of the member 2 and the side walls 24 reinforce the side walls of the article. The brace member 4, can be readily introduced into member 2 from either end thereof and pushed into the generally central position shown in Fig. 1.

35 The entire brace member 4 is formable from the single blank 28 shown in Fig. 2. The side walls 24 and strips 26 are formed by folding the blank 28 along score or fold lines 30 and 32. The strips 20 and 22 are formed by cutting the blank along lines 36 to form the free edges of the strips, along lines 38 forming continuations of fold lines 40 along which the strips remain joined to the base when pushed up from the blank and along lines 42 joining the termini of lines 36 and 38 and forming the ends of the strips. To provide interlocking means for the strips 20 and 22 small triangular sections 43 are cut out in strip 20 adjacent the ends of line 36 and similar small triangular sections 44 are cut out in strip 22 adjacent the ends of lines 38. The blank 28 is scored transversely of the strips 20 and 22 along lines 46. When the strips 20 and 22 are folded up from the blank 28 along the fold lines 40 and the free ends of each folded toward the other on lines 46, the notches formed by the removal of the triangular sections 43 and 44 permit crossing of the ends of strip 22 over the ends of strip 20 and serve to lock the strips into the four walled structure of the brace member.

Another construction of brace member embody-

3

ing the invention and suitable for use within a cover member of the general type of member 2 of Fig. 1 is illustrated in Fig. 4. As compared to the preferred construction of brace member illustrated in Figs. 1 to 3, member 4a of Fig. 4 requires less material for its construction but is less efficient in that it does not provide additional rigidity cross wise of the cover member. Also to insure central location in the cover member, the brace member 4a needs to be adhesively secured to the inner bottom wall of the cover member prior to assembly of the cover member. The brace member 4a comprises a structure having four upstanding walls 48 and outwardly extending flaps 50 integrally joined to the walls and adapted to be adhesively secured to the inner bottom wall of the cover member of the form. The brace member 4a is formable from the elongated blank 28a of Fig. 5. The blank 28a has a longitudinal fold line 52 thereon spaced from one edge 54 of the blank by a distance equal to the height of walls 48, four transverse fold lines 56 thereon extending from the edge 54 to the line 52 and defining the wall sections 48 and a tab 48a for adhesively securing terminal wall sections together; the blank being cut through along lines 58 extending from the termini of lines 56 to the edge 60 of the blank and defining, with line 52, the flaps 50.

To assemble the brace member 4a, blank 28a is folded on line 52 and then on lines 56 to bring tab 48a over the remote terminal wall section of the blank, to which it is then adhesively secured. The flaps 50 are then secured to the bottom wall of a cover member such as member 2 of Fig. 1, and that member then assembled to complete a form having its central portion reinforced by the member 4a.

The invention has now been described with reference to the preferred embodiment illustrated in Figs. 1 to 3 and to the modified construction illustrated in Figs. 4 and 5. Obviously, various changes could be made in the described constructions and in the proportions of the parts without departing from the scope of the invention as defined in the appended claims. For example, although the brace member of the form is preferably folded from a blank separate from that foldable to make the outer member of the new form, reinforcing strips like strips 20 and 22 of Figs. 1 to 3 could be folded up from the bottom wall of a single member to provide a brace member integral with the cover member. Such a construction would afford saving in material and labor in assembly and would be satisfactory where the additional strength and rigidity provided by the separate brace member is not required, as for example when light weight material is to be wrapped on the form. Various other modifications of the invention will be apparent to those skilled in the art.

The following is claimed:

1. As a new article of manufacture, a form about which sheet material may be wound comprising separable inner and outer members each of foldable material, said outer member being of the general shape of a board and said inner member comprising a base section, sidewalls integral with the base section and engaging the inner side walls of the outer member and strips integral with said base section folded up therefrom and interlocked with one another at both ends thereof to form an upstanding continuous wall, said inner member serving to reinforce the

4

outer member and prevent collapse thereof when the form is in use.

2. The article according to claim 1 wherein said strips of the inner member folded up from the base section comprise a pair of strips each of a width substantially equal to the inside depth of the outer member, each of said strips having notches therein adjacent the ends thereof, said notches interlocking with notches provided in the other of said strips to form a continuous walled structure.

3. A rectangular board-shaped form about which sheet material may be wound, having top, bottom and two side walls and an inner brace member disposed between and contacting the top and bottom walls thereof, said brace member comprising a pair of like strips each integral with a wall of said form, the ends of which are folded in towards each other and adapted to interlocking engage one another to form an upstanding continuous walled structure.

4. A form in accordance with claim 3 in which the strips are integral with the same wall.

5. As a new article of manufacture, a form about which sheet material may be wound, said form being composed entirely of foldable material and comprising an outer elongated member of relatively shallow depth and an inner brace member centrally disposed within said outer member, said brace member including a base portion of a width substantially equal to the internal width of the outer member and having strips integrally connected to said base section, each of said strips having its ends interlocking with corresponding ends of another of said strips to form an upstanding substantially ring-shaped brace.

6. A new article of manufacture, a form about which sheet material may be wound, said form being composed entirely of foldable material and comprising an outer elongated member of relatively shallow depth and an inner brace member centrally disposed within said outer member, said inner brace member being formed from a rectangular blank, said blank being cut through along lines defining three edges of each of two strips and along a section at each end of the remaining edge thereof, the ends of each of said strips being cut away to interlock with correspondingly cut-away ends of the other of said strips, said strips being adapted to be folded up from the blank along the uncut sections and said corresponding ends thereof beyond said uncut sections folded toward each other and interlocked.

JACOB M. FIELD.
